US0D1069656S

(12) **United States Design Patent** (10) Patent No.: **US D1,069,656 S**
(45) Date of Patent: ** Apr. 8, 2025

(54) **ELECTRIC WHEELCHAIR**

(71) Applicant: **Shanghai Bangbang Robotics Co., Ltd**, Shanghai (CN)

(72) Inventors: **Jianguo Li**, Shanghai (CN); **Zhefu Zhang**, Shanghai (CN); **Xianyu Su**, Shanghai (CN)

(**) Term: **15 Years**

(21) Appl. No.: **35/519,355**

(22) Filed: **Aug. 11, 2023**

(80) **Hague Agreement Data**

Int. Filing Date: **Aug. 11, 2023**

Int. Reg. No.: **DM/233576**

Int. Reg. Date: **Aug. 11, 2023**

Int. Reg. Pub. Date: **Dec. 15, 2023**

(51) **LOC (15) Cl.** **12-12**

(52) **U.S. Cl.**

USPC **D12/131**

(58) **Field of Classification Search**

USPC D12/128, 131, 133

CPC A61G 5/04; A61G 5/041-047; A61G 2005/048

(57) **CLAIM**

The ornamental design for an electric wheelchair as shown and described.

DESCRIPTION

1. Electric wheelchair

1.1 Front

1.2 Back

1.3 Left

1.4 Right

1.5 Top

1.6 Bottom

1.7 Perspective

1.8 Perspective

1.9 Folded view

FIGS. 1.1-1.9 of the design are shown in greyscale, and the design does not claim protection for a specific coloring.

1 Claim, 9 Drawing Sheets
